HYDRAULIC BUMPER JACK

Herbert E. Page, Dayton, Ohio

Application March 13, 1947, Serial No. 734,464

4 Claims. (Cl. 60—52)

1

This invention relates to a hydraulic jack. It has special application to hydraulic bumper jacks.

An object of the invention is to obtain a bumper jack which will be low in collapsed height and yet will have sufficient lift to raise the modern car from the ground. This is of particular value in connection with cars embodying knee action on the front end, requiring a greater lift in order to raise the front wheels clear of the ground.

Another object of the invention is to permit raising and lowering of the jack without use of the hands.

A further object is to enable lowering of the jack by use of the same actuator, for example a foot pedal, which is used to raise the jack.

Still another object is to incorporate in the jack a load limit relief feature which will prevent overloading.

A still further object is to produce a bumper jack with all operating parts contained in the base body and with an integrally formed reservoir avoiding the necessity of embodying a special reservoir at the top of the jack. A feature of the jack, as so characterized, is that it may be used as an extension device by applying the load directly to the top cap.

Other objects and structural details of the invention will appear from the following description when read in connection with the accompanying drawings wherein:

Fig. 1 is a view, in vertical longitudinal section, of a bumper jack embodying the present invention, and is taken substantially along the line 1—1 of Fig. 2;

Fig. 2 is a top plan view of the jack of Fig. 1;

Fig. 3 is a detailed view of the base section of the jack, in vertical longitudinal section, and taken substantially along the line 3—3 of Fig. 4;

Fig. 4 is a view in vertical cross section taken substantially along the line 4—4 of Fig. 1;

Fig. 5 is a view of the base section of the jack in rear elevation;

Fig. 6 is a detailed fragmentary view in vertical longitudinal section, showing a modified apparatus for operating the pumping piston of the jack;

Fig. 7 is a view similar to Fig. 6 showing another form of pumping piston operating means; and

Fig. 8 is a view in rear elevation of the device of Fig. 7.

Referring to the drawings, in the embodiment of Figs. 1 to 5 inclusive, a hydraulic jack com-

2

prises a base 1 receiving one end of an outer reservoir tube 2, the tube 2 being fixed to base 1, as by welding or the like. A tube 3 surrounds tube 2 in contacting relation therewith and supports near its upper or outer end a pair of adjustable clamps 4 and 4b. The clamps 4 and 4b are arranged in opposed relation, being adapted to grip therebetween a bumper E. The clamps 4 and 4b are provided with handles 4a and 4c respectively, the construction and arrangement of the parts being in that respect a conventional one to effect adjustment of the clamps along the length of tube 3.

A ram sleeve 5 is screwed into the base 1 at its lower end and receives at its upper or outer end, with a threaded connection, a bushing 6. Ram sleeve 5 is inwardly spaced from tube 2, while bushing 6 is flanged to engage the outer end of tube 2. Within ram sleeve 5 and spaced therefrom is a piston rod 7 slidably mounted in bushing 6. The lower end of piston rod 7 has a spacer 8 and a cup washer 9 fixed thereto. At its upper or outer end, piston rod 7 carries a cap 11, fixed to the rod by means of a screw stud 10.

The periphery of cap 11 is threaded for attachment to the upper end of tube 3, the assembly comprising tube 3, cap 11, rod 7, spacer 8 and washer 9 being thus connected for motion as a unit.

At the base, the jack supports a foot operated lever or treadle 12, pivotally mounted on a rod 13 carried at the rear of the base. The lever 12 is formed with a pair of side arms embracing the base of the jack, which arms are connected at the end adjacent rod 13 by a web 12a, and which at the front of the jack terminate in a serrated portion 12b. Carried at the rear of the lever 12, beneath the web 12a, is a roller 14 adapted to engage the closed projecting end of a piston 15 reciprocable within a cylinder 25 formed within the body 1. Referring particularly to Fig. 3, a spring 16 is arranged within cylinder 25 and presses piston 15 outwardly into contact with roller 14.

The space between the ram piston rod 7 and the ram sleeve 5 and between ram sleeve 5 and tube 2 are respectively identified as chambers 17 and 18 and comprise the reservoir of the jack, these spaces being normally filled with a hydraulic liquid. A port 19 near the upper end of sleeve 5 connects the reservoir chambers 17 and 18. Another port 20 (Fig. 4) connects the reservoir chamber 18 to a chamber 21 within body 1, which latter chamber is referred to for reasons

55 which will hereinafter appear as the high pres-

sure relief and lowering valve chamber. Communicating passages 22 and 24 in body 1 connect chamber 21 to cylinder 25 within which piston 15 reciprocates. A check valve 23 between passages 22 and 24 is arranged to close toward chamber 21. A port 26 also is provided connecting cylinder 25 to chamber 21. A poppet valve 28 within port 26 is arranged to close in the direction of cylinder 25 and is urged to closed position by a relatively heavy spring 27. A further port 29 (Fig. 1) is provided connecting cylinder 25 to a chamber 30, another port 31 leading from chamber 30 to a chamber 32 beneath the ram piston assembly comprising spacer 8 and washer 9. A poppet valve 34 in port 29 is arranged to close toward cylinder 25 and is pressed to closed position by a relatively light spring 33. A light spring 35 acts on poppet 23 to urge this valve closed.

Arranged between and supported by the side rails of the treadle 12 is a lever 36 pivotally mounted on a cross pin 37. A spring 36a tensioned between pedal portion 12b and a forwardly extending finger of lever 36, urges the lever in a clockwise direction as viewed in Fig. 1 to place a transverse portion 36b thereof slightly above the level of pedal 12b. Further, a vertical extension 38 of lever 36 is normally aligned with an upstanding lug 39 integral with base 1. The arrangement is such that if treadle 12 is depressed without rocking lever 36 from its position shown in Fig. 1, projection 38 will contact lug 39 and so limit downward movement of the treadle and correspondingly limit the extent of inward motion imparted to piston 15. Should the foot of the operator be so placed as to depress and rock lever 36 at the same time treadle 12 is depressed, projecting portion 38 will have moved out of alignment with lug 39 and an additional motion thereby permitted treadle 12 and piston 15.

The operation of the jack is as follows. Starting from the position shown in Fig. 1, wherein treadle 12 is shown in a lower depressed position, the spring 16 acting on piston 15 will serve, when foot pressure is removed from pedal 12b, to push roller 14 outward, and cause treadle 12 to rock about pivot 13 and rise to the position shown in dotted lines in Fig. 1. When the piston 15 moves to the right, it will draw hydraulic fluid from the reservoir chamber 18, the fluid passing through port 20 and through chamber 21 and port 22 past ball valve 23 into cylinder 25. If the treadle 12 is again depressed it will cause the piston 15 to be moved inward within cylinder 25, and, since the ball valve 23 will now be seated by spring 35, the oil trapped in the cylinder 25 will be forced out the port 29 past poppet valve 34 and through port 31 into chamber 32. Repeated operation of the piston 15 in this manner forces additional fluid into chamber 32, compelling piston 7 and the parts connected thereto to rise.

It will be noted that the pressure developed in the cylinder 25 by pumping action of piston 15 will also act through the port 26 against the poppet valve 28. Since the spring 27 acting on valve 28 is much heavier than the spring 33 acting on valve 34, valve 28 will not be unseated by the pressure of the oil during normal operation of the jack. However, if the jack is overloaded and the pressure within the cylinder 25 becomes excessive then the spring 27 will allow the poppet 28 to move off its seat in port 26 and allow oil to flow therethrough into chamber 21 and port 20 back to the reservoir chamber 18. There is thus

provided an overload safety limit which may be made variable by adjustment and selection of the spring 27.

It will further be noted that as the piston assembly on the lower end of rod 7 rises, fluid is caused to flow from reservoir chamber 17 to chamber 18 to replenish the supply which has been withdrawn from chamber 18 in order to raise the jack.

When it is desired to lower the jack, the operator depresses lever 36 as a part of the same action by which he presses treadle 12 downward, thus causing projection 38 on lever 36 to avoid engagement with projection 39 and allowing roller 14 to move farther to the left in acting on piston 15 than is possible during the normal pumping stroke. This additional motion of lever 12 and roller 14 causes piston 15 to move approximately its full distance into cylinder 25 during which motion it engages a projection 28a on poppet valve 28. Acting through projection 28a, poppet valve 28 is positively forced from its seat. At the same time, piston 15 engages a similar projection 34a on poppet valve 34 and likewise moves this valve from its seat in port 29. While treadle 12 is held depressed and poppet valves 28 and 34 so held from their seats, hydraulic fluid flows from the pressure chamber 32 through port 31 and chamber 30 past poppet valve 34 into cylinder 25 wherefrom it may escape through port 26 past poppet valve 28 into chamber 21 and reach the reservoir chamber 18 through port 20. The release of pressure in chamber 32 allows the extensible ram assembly to descend under load to its normal position.

In Fig. 6 another device is shown for moving the pumping piston 15 farther to the left than during its normal pumping motion in order to lower the jack. In this instance, an eccentric fulcrum 40 is utilized for mounting lever 12, a handle 41 being attached to the eccentric connection. With a limited movement of the lever 12 about pivot 40 the piston contacting roller or rod 14a may be caused to assume different initial starting positions. Thus, moving the handle 41 from the dotted line position to that shown in full lines will enable the piston 15 to be moved farther to the left with the same extent of movement of the treadle 12.

Figs. 7 and 8 show a somewhat similar arrangement except that in this embodiment the handle 41 is replaced by an added foot pedal 42, normally held upward by a spring 43 but which may be depressed as a part of the same motion by which treadle 12 is depressed. An eccentric fulcrum 44 will operate to give piston actuating roller 14b an additional travel sufficient to effect a full inward movement of piston 15 and lowering of the jack.

What is claimed is:

1. In a hydraulic jack incorporating a liquid reservoir and a movable ram, a body, means in said body defining in conjunction with said ram a pressure chamber, a cylinder in said body, a piston reciprocable in said cylinder, first and second passages providing communication respectively between said reservoir and said cylinder and between said cylinder and said pressure chamber, a third passage between said cylinder and said reservoir, a valve in the first passageway seating toward said reservoir, spring loaded valves in said second and third passages seating toward said cylinder, means defining a normal travel for said piston in said cylinder, and means

responsive to an overtravel of said piston for moving said spring loaded valves from their seats.

2. A hydraulic jack according to claim 1, characterized in that said last named means includes projections on said valves extending into said cylinder in position to be engaged by said piston during said overtravel thereof.

3. In a hydraulic jack incorporating a liquid reservoir and a movable ram, a body, means in said body defining in conjunction with said ram a pressure chamber, a cylinder in said body, a piston reciprocable in said cylinder, valve controller means for supplying said cylinder with liquid from the reservoir, a passage leading from said cylinder to said pressure chamber and another passage leading from said cylinder to the reservoir, spring loaded poppet valves in said passages closing toward said cylinder, and projections on said valves extending into said cylinder into cooperative relation with said piston, said piston being capable of a pumping motion without engagement with said projections and being adapted for an additional motion in one direction when it is desired to lower the jack during which added motion it engages said projections and moves said valves from their seats.

4. A hydraulic jack according to claim 3, characterized by operating means for said piston comprising an actuating lever, means defining a normal range of movement for said actuating lever, and means for causing said lever to operate in another range of movement in which it may impart said additional motion to said piston.
